UNITED STATES PATENT OFFICE.

HARMON D. MOÏSE, OF SUMTER, SOUTH CAROLINA, ASSIGNOR OF ONE-HALF
TO ARCHIE CHINA, OF SAME PLACE.

AXLE-LUBRICATOR.

SPECIFICATION forming part of Letters Patent No. 635,571, dated October 24, 1899.

Application filed July 27, 1899. Serial No. 725,309. (No model.)

To all whom it may concern.

Be it known that I, HARMON D. MOÏSE, a citizen of the United States, residing at Sumter, in the county of Sumter and State of 5 South Carolina, have invented a new and useful Improvement in Axle - Lubricators, of which the following is a specification.

My invention is an improvement in axles, and particularly in means whereby to lubricate the same, and relates especially to the means for supplying the lubricant to the wick or absorbent strip lying in the channel or groove formed in the spindle of the axle.

The invention has for an object to provide a 15 simple novel construction whereby to utilize capillary attraction in feeding the oil from the reservoir to the strip lying along the spindle.

The invention consists in certain novel constructions and combinations of parts, as will 20 be hereinafter described, and pointed out in the claims.

In the drawings, Figure 1 is a vertical longitudinal section of an axle and spindle embodying my invention, parts being broken 25 away. Fig. 2 is a cross-section on about line 2 2 of Fig. 1, and Fig. 3 illustrates a construction in which the reservoir for the oil is separate from the axle and is secured thereto by the devices which will be presently 30 described.

The axle A is provided at its outer end with the spindle B, at the inner end of which spindle may be formed the sand-guard C, as shown. In the upper side of the spindle I 35 form the groove or channel D for the absorbent strip or wick K. This channel D extends lengthwise of the spindle and at its inner end nearly to the sand-guard C, before described. The axle A is provided at the inner side of the sand-guard C with an enlargement upon its upper side to form the reservoir E for the lubricant. At its inner end the enlargement forming the reservoir has a square shoulder at E', while the outer end of 45 the enlargement is curved downwardly at E², conforming in shape to that usually given the outer end of the wooden axle cap or bolster ordinarily secured on vehicle-axles. In the present instance the wooden cap or bolster F 50 abuts at its outer end against the inner square end of the reservoir E, and the outer

clip G embraces the adjacent ends of the reservoir and the cap-bar F and tends to brace such parts firmly in position.

In forming the oil recess or cavity in the 55 reservoir E the same is furnished by drilling or boring a hole E⁵ longitudinally from the inner square end E' of the reservoir E nearly to the outer end of such reservoir, as best shown in Fig. 1 of the drawings. When this 60 is done, the inner end of the hole E⁵ is closed by a plug E⁶, which may be brazed in place or otherwise secured, as may be desired. I then form in the upper side of the reservoir E, near its outer curved end, an opening H' 65 for the filling-cap H. This opening H' permits the operation of a drill by which the hole or passage I may be formed, which leads diagonally downward and outward and intersects at I' the hole I², which extends longitudinally inward from the inner end of the channel D, formed in the upper side of the spindle B. The hole I opens into the oil-reservoir immediately upon an upwardly-facing seat or shoulder J, which lies directly below 70 the filling-cap H, and the wick K, which may be a separate wick or, if desired, a continuation of the absorbent strip lying within the channel D, extends over the shoulder J in position to be compressed by the filling-cap 75 H when the latter is turned inward to close the opening H'. By this means the wick can be compressed to any desired degree to regulate the feed of the oil. In order to permit this regulation of pressure and yet permit 80 the cap H to be screwed home at all times, I prefer to provide said cap at its inner end with an adjustable presser portion H² in the form of a plug which can be screwed into the cap to any desired degree to regulate the 85 pressure upon the wick. This will be understood from Fig. 1, from which it is manifest the plug H² may be set as shown in said figure, where it exerts little or no pressure upon the wick K, or said plug may be adjusted 90 down to exert any desired degree of pressure upon the wick in order to regulate the flow of oil as may be desired. The wick K is thus directed into the oil from a point above the level of the oil, so the latter will only be fed 95 outward by the wick by capillary attraction, thereby avoiding any waste of oil in the op-

eration of the device. It will also be noticed that the reservoir does not form any unsightly projection upon the axle, but conforms generally to the appearance of the outer end of 5 the wooden cap or axle section, as will be readily understood from Figs. 1 and 2 of the drawings.

While it is preferred to form the reservoir integral with the axle, as shown in Figs. 1 10 and 2, it may be desirable in some instances to construct such reservoir separately and apply it to the axle, as shown in Fig. 3. In the construction shown in such figure the reservoir L conforms in external shape to the 15 usual form of the outer end of the wooden cap or bolster of the axle. Near its outer end the reservoir L has an opening L' extending outwardly from a shoulder L² and arranged in register with a threaded opening M in the 20 axle, which opening M communicates with a hole M', leading from the groove or channel in the spindle. A tube N is shouldered at N' to abut a washer placed against the shoulder L² and is provided with a small extension 25 or nipple N², which threads into the opening M. This tube N operates to direct the wick to an elevated position within the oil-reservoir and also serves as a means for securing the 30 outer end of the removable reservoir to the axle. For convenience in inserting the tube N, I provide the opening for the filling-cap in line with the opening M and also provide the pressure-plug in the inner end of such 35 cap, which operates against the inner end of the tube N, which thus forms a seat for the wick, against which the regulating-pressure of the plug may be exerted.

A clip O may be provided for securing the reservoir in place at its inner end, its outer 40 end being secured by the tube N, as before described.

Having thus described my invention, what I claim, and desire to secure by Letters Patent, is—

45 1. An axle provided with a spindle having the longitudinal groove or channel for the absorbent wick or strip and having upon the

axle at the inner end of the spindle an integral upwardly-projecting portion forming the oil-reservoir, the inner end of such reservoir 50 being squared and an opening being formed from such end providing the oil-cavity, means for closing the inner end of the reservoir, an opening being provided in the upper side of the reservoir near its outer end for the filling- 55 cap and a hole being extended from a point in line with such opening diagonally downward and outward and communicating with a hole leading from the wick-channel in the spindle, and the filling-cap substantially as 60 set forth.

2. The combination of the axle having an oil-reservoir, a wick-channel leading therefrom, and a bearing for the wick at the inner end of said channel, and the filling-cap 65 having at its inner end an adjustable portion arranged for pressure against the said wick-bearing whereby it may be operated to compress the wick whereby to regulate the feed of the lubricant, substantially as set forth. 70

3. An axle having its spindle provided with a wick-channel and provided upon its upper side at the inner end of said spindle with an integral oil-reservoir having within it a shoulder or bearing J, provided above said shoulder with an opening for the filling-cap and also with a passage I leading to or establishing communication with the channel in the 75 spindle, and the filling-cap fitted in its opening above the shoulder J, substantially as set 80 forth.

4. An axle having its spindle provided with a longitudinal groove or channel and provided at the inner end of said spindle with a reservoir having a cover provided with a feed-opening and cap and provided within said reservoir opposite said opening with a shoulder or bearing for the oil-feeding wick, and the wick, substantially as set forth. 85
